UNITED STATES PATENT OFFICE.

WILLIAM T. MADDOX, OF ALEXANDRIA, LOUISIANA.

CARD-GAME APPARATUS.

1,119,183.

Specification of Letters Patent.

Patented Dec. 1, 1914.

Application filed May 17, 1913. Serial No. 768,329.

To all whom it may concern:

Be it known that I, WILLIAM T. MADDOX, citizen of the United States, residing at Alexandria, in the parish of Rapides and State of Louisiana, have invented certain new and useful Improvements in Card-Game Apparatus, of which the following is a specification.

This invention relates to cards to be used for playing an interesting, amusing and instructive game and one which will tax the mental powers to get a solution of the same, as the cards may be used, under certain conditions as a puzzle requiring study and care to enable solution.

A further object of the invention is to provide a number of cards adapted to be divided into two separate packs, one pack being subdivided into a plurality of suits, the cards of each suit having pictures thereon representing a sequence of events in a story, the said cards, during play, adapted to be placed, face down, one suit directly beneath the other, the cards being mixed or arranged disorderly. The other card pack consists of as many cards as there are suits, the said cards being hereinafter referred to as blanks, each blank card containing descriptive matter, in writing, relating to the different stories represented upon the cards of the several suits, the said blank cards, when in play, being placed, face up, and to the left of the several suits so as to convey to the player of the game, the story to which the suit along side of which it is placed, appertains.

The invention still further resides in providing each card with a number, the numbers being arranged in arithmetical progression to indicate the order in which the cards should be placed in following the trend of the story.

In the drawings, Figure 1 illustrates one of the cards containing the descriptive matter and Figs. 2, 3, 4, 5, 6, 7, and 8 represent a series of the cards arranged in arithmetical progression.

The cards illustrated in Figs. 2 to 8 inclusive are adapted to contain pictures representing a sequence of events in a story, there being as many stories as there are suits, and the card illustrated in Fig. 1 is adapted to describe, in writing, merely what the pictures represent. As a general illustration: On the first card of the picture suit Fig. 2 is the representation or picture of a dog; on

the second card of the suit is the picture of a cat; on the third card the picture of a rat; on the fourth card the picture of a cat in full chase after the rat; on the fifth card the picture of a dog determined to catch the cat; on the sixth card the picture of the rat which has just time enough to enter its hole under the root of a tree to avoid being caught by the cat; and on the seventh or last card is the picture of the cat closely pursued by the dog, the cat taking advantage of the tree to make its escape from the dog who sits down looking dismayed. The above arrangement of the several picture cards and the descriptive cards relating thereto, is provided for according to the number of card suits used in the game, the pictures or stories, however, in each suit being different.

Numerals ranging in arithmetical progression are arranged one in the lower left hand corner of each picture card of the several suits, the numbers on the picture cards corresponding to the numbers on the descriptive card, the said numbers on the latter being arranged in proper rotation as is clearly illustrated in Fig. 1 of the drawings.

The arrangement of the cards, before play, is as above described: namely, the blank cards, faces up, are arranged one directly beneath the other, while the picture cards, there being seven picture cards to each suit, at one side of the several descriptive cards, the said picture cards being arranged disorderly, faces down, so that the numbers thereupon will not follow in arithmetical progression.

To play the game, let a number of players get around a table, and let each player in turn have an opportunity in locating a certain picture card. One may accidentally guess the correct card and the others be ignorant of the fact. He might make two or more correct guesses in succession and the balance of the players would think he had worked out the puzzle or game. After player number 1 has had his guess, player number 2 should step into his place (each one taking the place of his neighbor) and arrange the cards according to his notion or idea of the correct manner in which they should be placed. Much merriment may be caused by different ones turning the wrong card. In this manner let each one take his place at the table and keep it up as long as desired.

This is a game which is not hampered for want of players or partners, each being adapted to one or more players. The serial cards are placed on the table by a little 5 arithmetical calculation, and each one can also be discovered by the same calculation to a certainty, though confusion will cause errors and if one is not careful, he will make mistakes and will have to pay the penalty 10 the game exacts.

The object of the game is to arrange the picture cards in proper order, the numbers thereupon following the proper progression from one to seven inclusive, the cards of 15 each suit being properly arranged and in accordance with the descriptive matter contained on the card placed along side thereof, the order of the picture cards being the same as that set forth on the descriptive card relating thereto.

When utilized as a puzzle one's ingenuity is taxed in placing the cards correctly on the table, face downward, the player finding it interesting, amusing and instructive in that 25 he will be first to work out the problem, caused by the picture serials and the numerals arranged upon the card. The object of the game is to arrange the cards according to the description contained on the descriptive card with the picture cards arranged in proper rotation, which serial containing the pictures being composed of seven picture cards.

It will be seen from the above, taken in 35 connection with the accompanying drawings that an interesting instructive and amusing game is provided by the use of cards arranged as hereinbefore described; that to carry out the object of the game it is necessary to arrange the cards in arithmetical 40

progression, the cards of each picture series being separate; and that a game of "solitaire" may be played from one and the same pack of cards used for playing the game.

Having thus fully described my invention, what I claim as new and desire to secure by Letters Patent, is:—

1. A card game including a plurality of card suits, each card suit consisting of cards having pictures thereon representing a sequence of events in a story. 50

2. A card game including a plurality of card suits, each card suit consisting of cards having pictures thereon representing a sequence of events in a story and a card adapted 55 to contain descriptive matter for each suit, the descriptive matter upon the said card relating to the representations upon the cards of the suit.

3. A card game including a plurality of 60 card suits, each suit consisting of cards having pictures thereon representing a sequence of events in a story, each card being provided with a number, the numbers being arranged in arithmetical progression to indicate 65 the order in which the cards should be placed in following the trend of the story, a descriptive card for each suit, the said descriptive card containing descriptive matter relating to the story, the said descriptive 70 card also containing numerals arranged in arithmetical progression to indicate the order in which the picture cards of the suit should be arranged.

In testimony whereof I affix my signature 75 in presence of two witnesses.

WILLIAM T. MADDOX.
